UNITED STATES PATENT OFFICE.

MYRON F. HILL, OF NEW YORK, N. Y., ASSIGNOR TO WESTERN ELECTRIC COMPANY,
INCORPORATED, OF NEW YORK, N. Y.; A CORPORATION OF NEW YORK.

AUTOMATIC TELEPHONE EXCHANGE.

Refiled for abandoned application, Serial No. 523,852, filed September 22, 1894. This application filed November 25, 1922. Serial No. 603,178.

Refiled for abandoned application Ser. 523,852, filed Sept. 22, 1894.

The object of my invention is to produce an automatic exchange that will fulfill the demands of commercial telephony. In accomplishing this result I have carefully guarded the system against all possibility of interference between subscribers, have simplified the apparatus so that it is cheapened and can be easily comprehended and cared for by the ordinary electrician, have reduced the wiring necessary to an exchange, and have increased the speed of establishing connections between subscribers.

To secure the best results of my invention the subscribers of the exchange are divided into groups, each group in a different locality. Each group of subscribers is provided with a switching set, or a set of loop or link connectors, adapted to interconnect the subscribers in pairs. By means of this switching set any subscriber in a group may connect himself with any other subscriber in his group. The switching sets of the different groups may be interconnected by trunk lines,—a different set of trunk lines between each two switching sets, so that a subscriber in one group may connect himself with any subscriber in any other group. With this organization the trunk lines may be identical with those to be described below. This specific organization, however, I do not claim in this patent.

The organization which I prefer for the purposes of this patent is as follows: The groups of subscribers above described are termed for convenience groups of the first order. These switching sets of the groups of the first order are again divided into groups, each group in a different locality. These groups are termed for convenience groups of the second order. Each group of the second order is provided with a switching set or a set of loop or link connectors, adapted to interconnect the various groups of the first order which lie within the groups of the second order. A main central station is provided through which the groups of the second order may be connected by means of trunk lines.

All subscribers are thus connected with one another through one or more central stations. In this way the system is made up of radiating trunk lines running between

the main central station and the switching sets of the second order; and additional trunk lines radiating from each switching set of the second order to the various switching sets of the first order corresponding thereto.

These trunk lines afford means of connection downward from the main central station through the intermediate and sub-central stations to the subscribers' private lines. Here intermediate station is used as a convenient term for the switching sets of a group of the second order; and sub-central station is used as a convenient term for the switching sets of a group of the first order. In order that the subscribers may secure a connection with the main central station an additional set of trunk lines is provided running directly from the sub-central switching sets to the main central station. These trunk lines are used in one direction only, as illustrated below. They may be termed for convenience "short cut" trunk lines.

It is additionally noted that the trunk lines between any two switching sets may be from one to a dozen or more according to the needs of the system.

The switching sets of the groups of the first order, or, as I have termed them, the sub-central stations, may be located at different places within a village, town, or city; the switching sets of the groups of the second order, or, as I have termed them, the intermediate stations, may be located at convenient centers in these villages, towns, or cities; while the main central station may be located at any convenient central point, a county seat for example.

To use an illustration, a citizen of Eckington, D. C., is connected to a sub-central station in his immediate locality, and the various sub-central stations in Eckington are connected to an intermediate station located at some convenient center in Eckington. Georgetown is similarly provided with sub-central and intermediate stations. The different parts of Washington are similarly equipped. The main central station for the whole exchange may be located near the Patent Office as a convenient center. A subscriber in Eckington, in order to secure a connection with another subscriber in his own group needs only to operate the auto-

matic switching set of his own sub-central station. But, to secure a connection with a subscriber in another group in a different locality of Eckington he must connect himself by means of a trunk line of his sub-central station to the intermediate station, thence by means of a trunk line to the sub-central station of the group in which the other subscriber is located, and finally to the latter's private line.

And if the subscriber in Eckington wishes to secure connection with a subscriber in Georgetown, he must secure through the switching set of his sub-central station a connection to a trunk line running directly to the main central station located near the Patent Office; a second connection to a trunk line running from the main central station to an intermediate station in Georgetown; a third connection to a trunk line running from this intermediate station to the sub-central station of the group in which the Georgetown subscriber is located; and finally a connection to the private line of the desired subscriber.

It is necessary in the system described that the subscriber's outfit shall be adequate to the operation of switch apparatus to select any one of the greatest number of line circuits of any group; that is, if there are one hundred subscribers in each sub-central group, and if there are one hundred or less sub-central stations connected to each intermediate station, and one hundred or less intermediate stations connected to the main central station, each subscriber must be enabled to select any one of one hundred lines from any station, subcentral, intermediate, or main, and in order to do this he may be provided with what may be called an automatic signal transmitter or commutator by means of which he can transmit to any switching set with which he may be connected any one of one hundred different signals in order that the switching set may select any one of one hundred lines.

Another feature of my invention is the use of a plurality of trunk lines between any two stations, whether main, intermediate, or sub-central stations, as many as may be necessary for business, so organized that no effort is required on the part of the subscriber to select between them.

These trunk lines are so organized in the system that they may be used in either direction between the two switching sets with which they are connected, except in the one case already cited where the sub-central stations are connected directly with the main central station by trunk lines which may be used in one direction only, namely, from the sub-central stations to the main central station.

I do not limit my invention to use in a group system only as it may be used obvious-

ly with many subscribers and one central station.

The switching sets referred to of the central stations of the various orders correspond closely to loop or link or double plug conductors, used in the ordinary multiple switchboard system; that is, each switching set comprises a number of automatic links, so organized that when a subscriber has started to send in a signal for a connection, one end of a link corresponding to a link plug connects itself to his line to the exclusion of all other links of the switching set.

When a link has been connected through one of its ends to the subscriber's line, the subscriber, by working an automatic signal transmitter, or commutator, as I shall hereafter call it, causes the other terminal of the link to be connected to the desired subscriber, if he be in the same group, otherwise to a trunk line running to some other switching set.

To use the previous illustration, if a subscriber in a certain locality of Eckington starts to connect himself to another subscriber in his own group, one end of a link at his sub-central station is connected to his line. He then works his commutator, thus operating a selecting apparatus in the link so as to connect the other terminal of the link to the private line of the desired subscriber.

Again, if a subscriber in one locality of Eckington starts to connect himself to a subscriber in a different locality of Eckington, that is, in a different sub-central group but in the same intermediate group, one end of a link at his subcentral station is connected to his line. He then works his commutator, thus operating a selecting apparatus of the link so as to connect the other terminal of the link to a trunk line running to the intermediate station. As the subscriber starts to make the second signal, one end of a link at the intermediate station is connected to the trunk line already obtained. He then works his commutator for the second signal, thus operating the selecting apparatus of the link at the intermediate station so as to connect the other terminal of the link to a trunk line running to the sub-central group to which the desired subscriber belongs. Finally as the calling subscriber starts to signal for a third time, one end of a link at the sub-central station of the called subscriber connects itself to the trunk line last procured, and as the calling subscriber works his commutator for the third signal, a selecting apparatus at the called subscriber's sub-central station operates so as to connect the other terminal of the link to the called subscriber's private line.

Finally we have to consider the case where a subscriber in Eckington desires connection with a subscriber in Georgetown. As the

subscriber in Eckington starts to make the connection, one end of a link at his sub-central station is connected to his line. He then works his commutator for the first signal, thus operating a selecting apparatus in the link so as to connect the other terminal of the link to a trunk line running directly to the main central station. As he starts to make the second signal, one end of a link at the main central station is connected to the trunk line already obtained. He then works his commutator for the second signal, thus operating the selecting apparatus in the link at the main central station so as to connect the other terminal of the link to a trunk line running to the intermediate station in Georgetown, that is, to the group of the second order to which the Georgetown subscriber belongs. As the calling subscriber starts to make the third signal, one end of a link in the switching set at the intermediate station in Georgetown is connected to the trunk line last obtained. He then works his commutator for the third signal, thus operating the selecting apparatus in the link at the intermediate station so as to connect the other terminal of the link to a trunk line running to the sub-central station of the group of the first order to which the Georgetown subscriber belonged. Finally, as the calling subscriber starts to make the fourth signal, one end of a link at the sub-central station in Georgetown is connected to the trunk last obtained. He then works his commutator for the fourth signal, thus operating the selecting apparatus of the link at the Georgetown sub-central station so as to connect the other terminal of the link to the private line of the desired subscriber.

The links of all the switching sets are identical. And they cooperate with the various subscribers' commutators in the same way.

Each link contains four parts, the receiving circuit closer, the circuit controller, the selector, and the transmitting circuit closer. The receiving circuit closer forms an automatic connection between one end of its link and the calling line. In this way the receiving circuit closer corresponds closely to the plug of a link in manual systems which is inserted into the line of the calling subscriber. The transmitting circuit closer corresponds to the other plug of the link in manual systems and performs its function, that of connecting the other end of the automatic link to the line called.

The circuit controller takes the place of the cord switch in manual links, and switches the apparatus necessary to establishing a circuit into connection and out of connection with the link circuit. The selector performs the selecting function of the manual operator in selecting the line called from a large number represented at her board.

Each receiving and transmitting circuit closer plays over a switch board at each of which switchboards is located a line terminal adapted to be connected to said circuit closers. So that in a system of groups containing one hundred or less lines per group, each receiving and transmitting switch board contains the terminals of each line of the group.

At the receiving switch board the receiving circuit closer attaches itself to a calling line, and at the transmitting switch board the transmitting circuit closer connects itself to the called line. These two circuit closers are connected together by two wires forming a metallic circuit. Each circuit closer has two terminals adapted to be connected to two corresponding line terminals at its switch board. A separate switch board is provided for each circuit closer.

The subscriber's commutator at his substation when starting to send in a signal for a connection operates a circuit which in turn operates a receiving circuit closer causing it to close a connection with one end of its link to the calling line. Then the commutator sends in its signal which operates both the controller and selector, and these in turn cause the transmitting circuit closer of the link to connect the link to the called line, and then to send out appropriate signals indicating the fact, and finally to leave the circuit thus established ready for conversation.

If the transmitting terminal has been connected to a trunk line instead of to a subscriber directly, the circuit established is ready for a repetition of the operation of the commutator which causes a similar operation of another link at the next switching set to which the trunk line is connected.

The circuit controller like the usual cord switch loops a call generator into an established circuit to call the called subscriber, and then switches the generator out of the circuit again. The length of this call is more or less irregular, varying between one and four seconds in length. This call besides calling the wanted subscriber also informs the calling subscriber that his signals have secured the desired connection. If instead of signalling for a subscriber direct, the calling subscriber signals for a trunk connection, the generator operates the calling subscriber's bells only indicating to him that the trunk line connection has been secured and that the line is ready for another operation of the commutator.

If the called subscriber is sought for through any link, and if he is busy with some other connection, the link fails to establish the connection with him, and the controller does not loop the generator into the circuit. Hence the calling subscriber knows by the

absence of any return signal that the man he is after is busy and cannot be secured. By waiting a few moments, if the latter is through with his other connection, the desired connection is established and the calls sent out to both subscribers indicating the fact.

The controller performs another function. It sets a time limit apparatus to work which 10 at the end of some predetermined period disconnects the connected subscribers. This time limit is intended to guard against any failure of either subscriber sending in a disconnecting signal when he is through talking, also to guard against an undue prolongation of his connection or other abuse.

The circuit controller also introduces a restoring circuit into connection with the conversation circuit by means of which either 20 or both subscribers may restore the link apparatus to normal condition ready to establish other connections.

It consists further in economizing operating power, and in devices which operate 25 lightly, easily, certainly and rapidly. Other features are more particularly pointed out in the claims.

In the drawings Figure 1, represents in diagram view, the subscriber's apparatus at 30 his subscriber's station.

Figure 2 represents in diagram view, the connections for each subscriber at central station to the terminal switches.

Figure 2^a shows in detail a cross section 35 of one of the receiving terminal switch boards, showing the connections to a set of contacts thereon.

Figure 3 shows in diagram, the selector and circuit controller and other apparatus 40 for each automatic link.

Figure 4 shows in diagram view, the connections of a trunk line or of a second subscriber to the terminal switches.

Figure 5 represents a continuation of the 45 trunk line shown in Figure 4, and its terminals at a second central station.

Figure 6 shows in perspective part of the A-portion of a modified form of my selector.

Figure 7 shows part of the B-portion of 50 the selector.

Figure 8 shows a sectional view of a part of the said A-portion with electrical connections.

Figure 9 shows the arrangement of groups 55 of subscribers' sub-central stations around intermediate central stations, and main central stations permitting many subscribers, a million or more if necessary, to be connected together in one general telephone exchange.

Fig. 10, shows the form of escapement I use with the commutator C and circuit controller Cc.

In describing this system, I show how 60 it will be arranged when one hundred subscribers are grouped together to one and can

be connected through one sub-central station; likewise how one hundred sub-central stations are connected to a second central station. I even show how one hundred second 70 centrals might be connected to a third central, thus permitting one million subscribers to be arranged in the system. I would not, however, be understood as limiting this invention to an arrangement based upon hundreds for it is valuable in a system arranged with any number of communicating lines in a group that may be found to be desirable 75 be it three or ten thousand. Moreover, I do not limit myself to the use of numbers to designate the various subscribers or their position in a system with relation to sub or higher centrals, for letters or any other characters might be used to designate their relation to the system. A system arranged upon the basis of hundreds seems however, to be 80 preferable, as it strikes a mean between unnecessary operations on the part of calling subscribers and unnecessary complication of instruments.

Each subscriber is provided with the ordinary transmitter, receiver, magneto if so desired and bells used in the present outfit. In addition to this outfit he is provided with a circuit changer or commutator and a key board. He is connected by wires a and b of 85 a central exchange to electro-magnetic devices through which he is enabled to obtain connection with any other desired subscriber in the system. The side of the metallic circuit a is connected through contact points ax and ay, adapted to be opened upon the operation of the magneto mg. From thence, the side a of the metallic circuit is connected to the switch lever S¹. The side a of the metallic circuit is also connected through the commutator when in a position of rest by contact springs b⁷ and s³⁰, resting upon the plate S¹². Whenever the commutator is in motion 90 the circuit of a is open at this point. The side b of the metallic circuit is connected to two branches h and h'. The branch h contains the transmitter Tr and the receiver Re and terminates in the contact point h⁴ normally out of connection with the switch lever. The other branch h' contains the signal bells si and has two sub-branches h² and h³. The branch h² terminates in a contact point h⁵ normally connected with the switch lever S¹. The other sub-branch h³ contains 95 the magneto mg normally on open circuit. When the magneto is operated the contact spring ax leaves the contact point ay due to the longitudinal movement of the magneto arbor, and the arbor makes contact by means of point mgx with the contact spring ax completing the circuit from wire b through the signal bell si in the branch h' to the wire a of the metallic circuit, permitting currents of electricity from the magneto 100 to be transmitted over the metallic circuit a 105 110 115 120 125 130

and *b*. I do not, however, regard the use of the magneto as necessary in this system, but I provide it as an additional signaling apparatus in case the automatic call, which is sent out from central, fails to bring the called subscriber to his telephone. In the branch *h*² is a contact lever *L* adapted, when the receiver is hung upon its hook, to be forced by its switch lever *S*¹ into contact with the point *L'* which is connected by wire *L*² to the earth *E*. When, however, the receiver is removed from the hook, the lever *L* is forced in the opposite direction and no contact is effected. In either case the insulated end of the switch lever *S*¹ is so shortened as to permit the contact lever *L* to pass to the other side thereof. The details of this circuit closer are not necessary to an understanding of its function. The organization of the subscriber's commutator is as follows: The metallic circuit is branched by two wires *s*⁸ and *s*⁹ terminating in contact springs *s*⁶ and *s*⁷ adapted alternately, upon the rotation of the commutator, to come into contact with the conducting strip *s*¹⁰, thereby connecting one side or the other to the conducting strips of the commutator. The strip *s*¹⁰ has branch strips *s*¹¹. On opposite portions of the commutator, I arrange contact springs *s*⁴ and *s*⁵ of a key board *S*. The length of the branch strips *s*¹¹ on the circuit changer is so arranged that the contact springs *s*⁴ or *s*⁵ have their connections to contact springs *s*⁶ or *s*⁷ completed a variable number of times. In the drawing, as arranged, the left hand contact spring *s*⁴ and the left hand contact spring *s*⁵ are electrically connected to the contact springs *s*⁶ or *s*⁷ ten times; the next one of each series has its circuit completed nine times, the next eight and so on until the last spring in each set has its circuit completed but once. The number of variations in circuit connections may be adapted to the organization of the system.

I have shown a plug *P* connected by wire *p* to the earth at *E*. This plug *P* has transverse slots *p'* permitting the plug to close the circuit from the ground to the cross strips *s* or *s'* at any junction. Thus, by placing the plug over the left hand contact strip *s* and the top contact strip *s*, the right hand contact spring *s*⁴ of the circuit changer, and the right hand contact spring *s*⁵ of the circuit changer are grounded through the plug. I preferably use a special button at each junction, the button when pressed making contact with the cross strips and ground. The top rod *s* and left hand rod *s'* are permanently grounded by the wire *s*²⁹ so that whenever the commutator is rotated it completes a circuit over the wires *a* and *b* once. This, as will be more clearly described, establishes connection with a trunk line. When the commutator rotates,

the side *b* of the metallic circuit is grounded over the following path: wire *b*, branch *s*⁹, contact spring *s*⁷, strip *s*¹⁰, branch strips *s*¹¹, of the commutator, right hand contact spring *s*⁴, to the junction *O* of the keyboard, wire *s*²⁹, and the earth *E*. This circuit is completed once,—that is, the wire *b* is grounded at the subscriber's station once. After the contact strips *s*¹⁰ and *s*¹¹ have all passed beneath and beyond the contact springs *s*⁴ and *s*⁷, they create new circuit connections through springs *s*⁵ and *s*⁶ so that the side *a*, of the metallic circuit is grounded as follows: wire *a*, branch *s*⁸, contact spring *s*⁶, strips *s*¹⁰ and *s*¹¹, right hand spring *s*⁵ to the junction *O*, of the keyboard, wire *s*²⁹ to earth at *E*. In this manner wire *a* is grounded also once. If junction 14 had been selected and the plug *P* had been connected thereto the wire *b* of the metallic circuit would have been grounded two times and the wire *a* of the metallic circuit would have been grounded five times; the circuit in these cases passing through plug *P* to earth at *E*, in like manner if junction numbered 43 had been selected wire *b* would have been grounded five times and wire *a* four times making nine circuit connections at successive periods of time. Twenty is the highest number of circuit connections that is necessary when one hundred subscribers are connected to one sub-central exchange. This number would be varied according to the number of subscribers in the group. Slight changes in the circuit controller at central would permit a greater maximum number of connections to ground if desired.

The operating device for the commutator is constructed as follows. To a button *s*²⁴ is rigidly attached a rack *s*²³, in mesh with a pinion *s*²⁷ rigidly mounted on an arbor *s*²¹, the end of which is squared so that a clutch *s*²⁰ will freely slide longitudinally thereon, but will rotate always with the arbor. The other part of the clutch *s*²⁰ is rigid with the commutator, which is loosely mounted on said arbor so that it will freely rotate thereon. A spring *s*²⁸ holds the two parts of the clutch pressing against each other. A spring, *s*²⁵ pulls the rack downward, and a stop *s*²⁶ abutting against a post *s*²⁷ holds the rack and commutator in its normal position. When the rack is operated against the force of the stout spring *s*²⁵, it turns the pinion, which turns the arbor and the left hand part of the clutch *s*²⁰, the other part of the clutch and the commutator remaining stationary. When the pinion and arbor have completed a rotation, the two parts of the clutch reengage with each other and upon the release of the rack the pinion, clutch and commutator begin to rotate. An escapement, shown in Figure 10 is rigidly attached to the commutator to regulate its

speed in rotating. Suitable supports are provided for all parts. It is to be understood that any other apparatus accomplishing the same function, electrically speaking, 5 performed by the apparatus shown might be substituted for it. As the commutator begins its rotation, the circuit of the line wires is broken by the conducting piece s^{12} on the commutator passing away from the 10 brushes b^7 and s^{30} , and the line wire a is grounded through magnet Mr as follows:— wire a , contacts Rs^2 of the restoring button, wire s^{16} , brush s^{30} , brush s^{17} , magnet Mr , thence over the rest of wire s^{16} to earth at 15 E. This circuit would be made and broken were it not that the wire a was grounded through a battery at central, and the local magnet Mr was energized, attracting its armature s^{14} , thus placing the detent roller 20 s^{19} in the path of the stop s^{15} on the rear side of the commutator, holding the commutator from further rotation. When the circuit of the line wire a is broken at central from the battery, as will be described, 25 the detent releases the commutator which returns to normal position under the impulsion of spring s^{25} , making any circuit changes that the key board may determine. Breaking the circuit at Rs^2 will also release 30 the commutator in case an error has been made and the commutator has not been released from the central station. In releasing the commutator, the spring s^{18} withdraws the detent. 35 When the commutator is in its normal position as shown in Figure 1, the circuit of the line wires is closed through the brushes b^7 , and s^{30} and plate s^{12} . During 40 the rotation of the commutator this circuit is broken, thus splitting the circuit, so that either side may be used on a grounded circuit independently of the other, for operating purposes. A third wire may of course be substituted for the ground, but this is 45 unnecessary.

The roller may be omitted from the detent, and the end of the same rounded off smooth, and the spring may be omitted, if the stop s^{15} presents an inclined surface to 50 the rounded detent, sufficient to force the detent out of its path when not operated by the magnet.

Operating the subscriber's instrument in 55 this manner is followed by certain electro-magnetic action at the central station. To describe this action is the next object. Figure 2 represents the apparatus at the central station to which he is directly connected. In this figure the wires a and b are 60 the line wires which come from the subscriber's station connecting him to the central station to which I refer. The apparatus in this figure is shown in its normal position.

65 Each link is provided, see Figures 2, 4,

and 5 with receiving circuit closers Rs and transmitting circuit closers Ts , one of each for each link. By means of these switches a subscriber is enabled to obtain the use of central connecting devices and to connect 70 himself with another subscriber. Many circuit closers are mounted upon one arbor in practice. Each of these switches is composed of a rotating arm U , on which is mounted a tilting lever U' in proper bearings. On the lever is an armature m^3 adapted to be attracted by the magnet M^s in constant proximity to said armature. This lever U' has a heel u^4 resting on or in notches cut out from a collar u^5 rigidly fastened to the arbor. This collar supports the heel u^4 , and supports the arm U from dropping down out of position on the arbor U^2 . In the receiving circuit closers Rs , the terminals of the magnet M^s are connected 80 to the movable contacts on the arm U' of the pairs of contacts l^1, l^2, l^3, l^4 , respectively. The stationary contact of the pair l^1 is electrically connected to the brush l^2 . This brush passes successively over one of 85 the insulated contacts of each set of contacts around the frame U^3 , and is shown in Figure 2 as resting on contact t^{92} of subscriber No. 92. In Figure 4 this brush is shown resting on contact Tt belonging to the 90 set of contacts of the trunk line T . In Figure 2 the contacts t^{92} are connected to branches of a local circuit t^5 which supplies battery power to the switch for operating 95 purposes, from dynamos or battery D' shown in broken lines in this figure, but being the same battery as D' in Figure 4. 100 The stationary contact of the pair l^5 is connected to a brush l which passes over a separate contact in each set of contacts on the switch board, shown in Figures 2, 2^a, and 4 as a^2 . This contact is connected to the branch wires u^7 of the respective operating 105 circuit. So that when the subscriber sets his commutator by pressing the button s^{24} for operation and the commutator is detained by the armature s^{14} , the line a is grounded over the following circuit; grounded source D , t^{14} (see also Fig. 3), circuit breaker u^4 , magnet Mt^2 , wire t^{14} , line wire a , normally closed circuit breaker Rs^2 , wire s^{16} , contacts s^{30} and s^{17} , magnet Mr , ground at E. The magnet Mt^2 closes the operating circuit 110 at u^3 as follows: battery D' , wire t^8 , contacts t^4 , wire t^5 , contact t^{92} , brush l^2 , contacts l^1 , magnet M^s , contacts l^5 , brush l , branch wire u^7 , wire u^6 , contacts u^3 , wire u , contacts u^2 , wire t^3 to the other pole of the battery D' . This circuit actuates the tilting lever U' 115 which first passes onto the subscriber's row of contacts upon any of the switch boards Rs , the switch arms or levers U' of the different switch boards being normally located at different radial positions around the shaft 120 which drives them. This operation breaks 125 each link. The subscriber's instrument 130

the circuit from battery D at u^4 , releasing subscriber's detent, s^{14} , which in turn releases the commutator S', so that it completes a single rotation. Before its inertia has permitted it to ground the line wires any further, the tilting lever has completed the circuit through the switch board to the selecting and other apparatus of the link as follows: The line wire a is connected by branch 5 a' and its contact, through the double brush U , ring contact l^9 , side La of the metallic link, and further normally open connections described in connection with Figure 3. The line wire b is connected through branch and 10 contact b' , contact ring l^{10} , to the side Lb of the metallic link, to further connections shown in Figure 3. The contact rings l^9 and l^{10} are common each to all the sets of contacts on the switch board. When the tilting lever U' has assumed its operative position 15 it establishes new and retaining local circuits, and breaks the operating circuits of this communicating line to all the links. For example the contacts l^8 and l^6 are closed, 20 and the following circuits established. Source of electricity D', wire t^3 , magnet Mt, wire t^6 , branch t^7 and its respective contacts on the switch board frame, brush l^{11} , contacts l^8 , magnet M^8 , contacts l^6 , brush l^{12} , 25 normally closed (see Figure 3) circuit controlling wires t^8 connected to ring contacts t^9 , thence by brush l^{13} to a contact connected to one of the branch wires v' of wire v , thence to magnet Mv , wire t^3 , battery D'. This circuit contains the two magnets Mt and Mv , which break the operating circuits u , u^6 , and t^5 by which this subscriber obtains the connection to any link. Since these operating circuits are broken after the operation of 30 one receiving circuit closer as described, it follows that no other circuit closer switch can be operated by the same line. In other words, the subscriber obtains connection automatically and exclusively with any one of a number of links that may be idle and in order. It is noted that each communicating line a , b , is connected by branches to each receiving switch board of the group to which he belongs and hence he has contacts on each 35 switch board Rs shown in Figures 4, and 5, as well as in Figure 2. I have deemed it unnecessary to show these connections as a different sections of the switch board would have to be illustrated, and it would be mere duplication. It must be noted also that there is a separate circuit v , u , t^5 and t^6 for each set of contact points on the switch board, or in other words, for each communicating line. But these circuits for a given line are common to all the switch boards to 40 which the subscriber is connected.

The lower two switch boards and connecting switches in Figures 2, and 5, and the upper two in Figure 4, Ts , are transmitting circuit closers, and through them the per-

son connected to the other end of one of the links, may obtain connection with another subscriber. For example, a person connected to Rs , Figure 4, may obtain connection with subscriber No. 92 whose connections are 45 shown in Figure 2. The line wires a , b of this subscriber are connected by branch wires and contacts a^2 and b^2 to each switch board of the switches Ts . These switches are very 50 much like the receiving switches Rs , except that they have less parts, and simpler circuits. The operating circuit may be traced as follows: wire b^{92v} , which branches from the link selector AB, and to which a source of power is connected by the calling subscriber, 55 as described more specifically hereinafter, contact on the switch board connected to wire b^{92v} (Fig. 1), of the frame of the switch boards Ts , the first brush l that comes into contact with it, magnet M^8 , contacts l' , brush l^2 , contact u^{92} , branches u^1 of wire u , to circuit breaker u^2 and to battery D'. This 60 circuit operates the switch, closing the two sides of the metallic link to the two sides of the communicating circuit of subscriber 92; 65 and also operates to close the pair contacts l^8 of the switch transferring the circuit from the operating wire u to the retaining wire v , as follows, from the magnet M^8 to the contacts l^8 , now closed, brush l^4 , branch v' of wire v , magnet Mv , wire t^3 , battery D'. This magnet breaks the operating circuit u , 70 so that after this action of one transmitting circuit closer no other transmitting circuit closer can be operated at the same point in its rotation. In other words, when one subscriber has been connected to a link no other person, through the same or through another link, can gain connection with him. 75

The stationary contacts of the pairs l^1 , l^3 , l^5 , l^6 , are in practice as those shown in the diagram, yielding or sliding contact springs, so that the retaining circuit is always completed before the operating circuit is broken, so that during the transfer of 80 circuits, electricity is flowing through the magnet M^8 . The diagram view shown is sufficient for this case.

A more detailed description and illustration of the switch boards is not deemed necessary, as they are broadly similar to those well known in the art of automatic exchange systems, and a sectional view of the frames showing my invention is sufficient. The connections to my switch board 85 are obviously different from the prior state of the art.

In Figure 3 is shown the selecting and circuit controlling apparatus of each link. The side La of the metallic link has a 90 branch j connected through the circuit controller Cc to magnet M^8 and thence to a dynamo or battery D. The side Lb of the link is connected by branch c through the circuit controller to other operating mag- 95

nets. From the line wire Lb the branch c runs through contact springs e , eo , resting normally upon contact plate i of the circuit controller, thence by wire c' to the magnet M' , thence by the same circuit c' point d^2 , connected to one pole of a source of electricity D , which is preferably either a chemical battery or a dynamo current according to the size of the exchange. The other pole of the battery is grounded as shown at E . A dynamo may be placed at one central point and furnish power to all the central stations of the exchange, the other pole grounded at the dynamo. I might, instead of using this dynamo current, use chemical batteries or any other source of electricity of a nature to operate electromagnetic devices. By this arrangement I effect a great saving in the cost of operating the automatic exchange.

When the line wire b is grounded by the subscriber for the first time upon the operation of the commutator, a circuit is found from the ground at E through the dynamo D , thence to point d^2 over the circuit c and c' as traced, including magnet M' , thence to link wire Lb and line wire b to ground at subscriber's station. A parallel circuit, from D , to magnet M , by wire c' , brush e^{11} to wire c , is simultaneously established. A current flowing through these circuits operates the two magnets mentioned. When magnet M' is energized it attracts the armature m' causing the switch Q to leave contact point connected to wire q upon which it normally rests, thus breaking the restoring circuit during connecting operations. Resistances may be interposed in any of the circuits to adjust the current flowing through them, as it is desirable, though not at all times necessary, to have circuits of substantially equal resistance.

We have followed out the consequences of the operation of magnet M' , but we have not yet followed out the consequences of the operation of the magnet M . This magnet, when energized by this first impulse operates the circuit closer m' before referred to, closing the local circuit m^1 from pole n^2 of battery D' through magnet M^1 , as follows: battery D' , circuit closer M^1 , wire q^3 , magnet M^1 , circuit breaker d^4 , open during restoration, circuit c^5 , to pole n^1 of battery D' ; magnet M^1 attracts armature m thereby operating the ratchet and pawl mechanism r^2 which rotates the circuit controller Cc . The contact plate i may pass away from the contact spring eo , breaking the circuit which has heretofore been completed to e at the first step of the ratchet r^2 . The contact plates i^2 , i^3 , i^4 , and i^{12} are brought beneath the contact springs e^2 , e^5 , e^9 and e^{12} , completing circuits thereby.

When the contact plate io breaks the circuit through the contact e and eo , circuit

c' is cut off from the link wire Lb so that no later impulse will keep the restoring circuit broken that may be intended to close such circuit.

In each link I employ a selector to enable any subscriber to select any one of a large number of circuits shown in diagram in Figure 3 lettered bv . The essence of this selector is a number of switch arms adapted to be operated each over a different row of contacts by means of motive power, and of a distinct motive power which causes a circuit to be established through one of said switch arms to the exclusion of the others. Or to put it in another way, a number of insulated electrical conductors adapted to be operated over rows of contacts, each conductor over a different row, and a common motive power for all of said conductors, and a second motive power adapted to establish a circuit through one of said conductors to the exclusion of the others. In my selector construction I prefer to have the switch arms make actual contact with each of the contacts in its row, and a separate switch arm to make connection with one of said first mentioned switch arms thereby establishing a circuit through it. But it is obvious that many changes may be wrought in the actual construction and method of operation.

It is obvious that a single motive power may operate one part of the selector, and then be adapted to operate the other and not the first. The primary part A is composed of a number of rows of contacts of primary order rigidly fastened to a support. I have shown ten of them in Figure 6; on each row is a number of contact plates, each plate being the terminal of a different branch line. I have shown eleven contact plates on each row but the first contact plate on all the rows is a dummy on which the contact arms normally rest. Over each row plays a contact arm b^{10} rigidly connected to an arbor so that as the arbor rotates all of the contact arms make contact simultaneously with contact plates upon their respective rows. The arbor is operated by suitable ratchet and pawl mechanism and by magnet M^{13} . The contact arms b^{10} are insulated from each other and each is electrically connected with a different contact plate on the dial or row of contacts B of primary order. Over this row B a contact arm b^7 is adapted to pass, operated by a ratchet and pawl device, actuated by magnet M^{12} . Connected with the arm b^7 is the line b^{16} which it is desired to be put in electrical connection with any one of the contact plates of the instrument A and with the branch wires connected to that contact plate. The contact arm b^7 when in electrical connection with one of the contact plates on the dial B , for example, plate b^8 , is thereby put in electrical connection with the contact arm of the instrument A .

electrically connected to that plate. When the contact arm of the instrument A is put in electrical connection with any contact plate b^{12} , a through circuit is established 5 from the wire lettered b^{16} to contact arm b^7 to the contact plate b^8 to the wire b^9 to the contact b^{10} , to the selected contact plate b^{12} and branch wire b^v . In the instrument A there are shown ten rows of contacts, each 10 having eleven contact plates, ten of which have branch wires; making in all one hundred contact plates for electrical connection. This number may be varied at will, but this 15 system being planned for one hundred subscribers, I have preferably shown one hundred contact plates by means of which the subscriber is enabled to obtain connection with any other subscriber belonging to his group. On the first row of contacts the 20 second contact plate lettered b^{11} and corresponding to character O or Ms on the subscriber's key board does not represent a subscriber, but represents any one of a number of trunk lines to a central station. A 25 line b^{14} leads from this contact plate and has branches b^{17} leading each to a contact segment of a different set of contacts on the transmitting switches TS, so that when electricity is supplied through the selector to 30 these contacts, the first one reached by the switch arm will cause a connection to be established to the particular trunk line it represents. The switch arm once operated cannot connect to another set of line terminals. The third contact plate on the first 35 row represents subscriber No. 1; the fourth contact plate represents subscriber No. 2; the eleventh contact plate represents subscriber No. 9. On the second row the first 40 contact plate is a dummy; the second contact plate represents subscriber No. 10 of the group; the eleventh contact plate represents subscriber No. 19. On the third row the last contact plate represents subscriber No. 45 29. In this way the first row contains contact plates representing subscribers 1 to 9; the second row represents subscribers 10 to 19, or represents the tens, the third representing the twenties, and so on up to one 50 hundred. This detailed description is necessary only to show one of the many different arrangements which I contemplate as possible when using these devices. It is obvious that other arrangements might be 55 used.

In following the operation of the commutator of the subscriber we have noticed that the line wire b is grounded at the subscriber's station a selected number of times. 60 We will suppose that subscriber No. 92 has placed his plug P upon the junction 43 of the switch board S as heretofore mentioned. The line wire b is then grounded five times. The first impulse passes over circuits c , c' 65 etc., as we have seen.

The five impulses from the dynamo D follow the circuit as follows: pole d^2 of the grounded dynamo, circuit wire g , magnet M^2 , circuit wire g , contact spring e' , and e , through contact plate i' , wire c , to link wire Lb , line wire b to ground at subscriber's station through the commutator and key board. The magnet M^2 , thus energized five times, closes the contacts ml^{22} of circuit ml^2 containing magnet M^2 , and the contact arm b^1 is advanced to the sixth contact plate b^{13} and thus put in connection through its appropriate wire b^{14} with the fifth contact arm b^{10} of the instrument lettered A. 70 75 80

The subscriber's commutator having 80
grounded the line wire b at his station a
determined number of times, it proceeds to
ground the line wire a also a determined
number of times. When the line wire a is
grounded, current from the dynamo D, one 85
pole of which is grounded at E as we have
seen, flows by way of point d^2 , circuit wire
 j , magnet M^3 over circuit j to contact springs
 e^5 , resting after the first advance of the 90
controller Cc on contact plate i^5 , thence to the
line wire a and to ground at subscriber's
station through his commutator and key
board. This circuit is completed to ground
by the subscriber's commutator four times, 95
as we have noted, when subscriber No. 43
is being called. This magnet M^3 is therefore
energized four times, correspondingly
closing at ml^{38} , the circuit ml^3 from battery
 D' , including magnet Ml^3 , advancing all of
the contact arms b^{10} by means of the ratchet 100
mechanism to the fifth contact plate on each
row, and circuit connection is established
from the line b^{10} through the contact arm
 b^7 , contact plate b^{13} , appropriate wire b^{14} ,
fifth contact arm b^{10} , its appropriate contact 105
plate b^{12} on the row of the instrument
A and the wire b_v connected to that contact
plate. In the meanwhile other circuits have
been established. The first step of the
controller Cc closes the following intermittent 110
circuit: battery D' , wire C^6 , circuit breaker
 d^4 , magnet M^1 , conductor g^3 , circuit breaker
 cb , thence to contact springs e^2 resting on the
plate i^2 , thence to springs e^{12} and plate i^{12} ,
thence by conductor c^6 to battery D' again 115
at N^2 . This circuit is made and broken by
the circuit breaker cb at regular intervals
energizing the magnet M^1 , at those intervals
and advancing the circuit controller step by
step, thus taking it beyond the control of 120

the subscriber unless he grounds his restoring circuit as hereinafter more fully described. This circuit breaker may be driven by a motor either directly geared thereto or may be operated by a clock or the rotating arbor ¹²⁵ *Ts*, or in any way that suggests itself to the skilled artisan there being one for each controller. As long as any subscriber in using the station apparatus, the circuit breaker *cb* is in operation except in case the ¹³⁰

time feature is omitted. In such case the contact plate i^2 is cut off so that after the signal has been sent out from CG, the circuit controller maintains in statu quo the circuits existing during connection and stops advancing. I arrange it preferably to close the circuit but once in every three seconds and I have provided a ratchet containing sixty teeth so that the circuit controller 10 makes a revolution once in three minutes; instead of this arrangement a ratchet with a different number of teeth might be used, or the circuit breaker cb might be operated at a different speed and thus vary the time 15 required for the circuit controller to make the full revolution.

At the first operation of the circuit controller, contact plate i^9 is brought beneath the contact springs e^9 , closing at this point 20 the following circuit from the battery D' , point n^2 , circuit wires c^6 and n , magnets M^4 , M^5 and M^6 , to the two point switch Q . If the two point switch Q were in its normal position this circuit would be continuous 25 through wire n^3 , and wire c^5 , thence to battery D' again. If now the magnet M' should alone operate to retract switch Q to its normal position thereby completing the circuit n and energizing the magnets M^4 , M^5 and M^6 ; these magnets would withdraw 30 the detents d^4 , d^5 and d^6 permitting the instruments A, B and Cc to return to normal position, and I provide a slight retardation for the circuit controller, so that it will not 35 resume its normal position till the other instruments are restored. This is effected by giving Cc some inertia; or an escapement may be used with good result, or another retardation device. I have not shown and 40 do not deem it necessary to show the details of my ratchet and pawl mechanism, but I prefer to use the ratchet and pawl shown in the patent to G. L. Anders, No. 240,878, date May 3, 1881, which holds the pawl normally 45 out of engagement with the ratchet but forces it into engagement with the ratchet when operated and locks the ratchet from further advance when the pawl has finished the length of its stroke. This restoring 50 circuit may be closed for operation at any time after the contact plate i^9 has passed beneath the contact springs e^9 so that if the subscriber makes a mistake in calling up another subscriber, or for other reasons 55 desires not to prosecute his connection, he may at once restore all his central office devices to their normal position. These restoring devices will be more fully referred to hereinafter. As the circuit controller continues 60 to rotate under the influence of the magnet M^1 , the circuit through the contact springs e^4 and e^5 , and contact plates i^7 and i^8 are broken, and the following grounding of the line wires a or b will have no effect 65 upon the central office connecting apparatus

operated at this point. Whatever occurs after these circuits are broken is due to local circuits. When the circuit controller brings the contact plate i^7 under the contact springs e^6 electricity from the dynamo D' is thrown 70 over the following circuit from point n^2 , wire c^6 , contact springs e^6 , and contact plate i^6 , circuit wire b^{16} , magnet M^{16} , contact arm b^7 , contact plate b^{13} , appropriate wire b^{14} , fifth contact arm b^{10} , its respective contact 75 plate b^{12} and branch wire bv .

Before following out the effects of this circuit, more additional explanation for the plan of connection of the various central instruments is necessary. Each link as we have seen, is provided with a selector as AB and two terminal circuit closers R_s and T_s respectively. From each selector to each set of contacts on the transmitting switchboard T_s run wires bv ; those wires bv which run to contacts of subscribers' lines being connected to independent contacts on A. At the switch boards T_s , in Figure 4, are shown these wires lettered bv . They represent one of the branch wires bv running from the selector of the link to the sets of contacts of a trunk line on the terminal switch boards T_s ; so that by means of these wires bv of the selector any subscriber who has obtained the use may bv connecting a source of electricity thereto, control through the contact piece b^{1w} and the contact brush l of the terminal circuit closer T_s , the magnet M^s . The circuit would then be from dynamo D' , point n^2 , wire C^6 , springs e^6 and plate i^6 of the circuit controller Cc , magnet M^{16} , wire b^{16} through selector A, B, through branch wire bv , shown in Figure 3, and shown in Figure 4, to the switch board T_s of the link, through contact plate b^{1w} and the brush l of the terminal circuit closer T_s to the magnet M^s ; thence to the normally closed pair of contacts l' to another brush l^2 connected thereto, on the contact arm of the circuit closer T_s , isolated from the first brush, thence by contact plate u^1 on the switch board and wire u , circuit breakers u^9 , u^2 , to t^3 , battery D' . This magnet M^s will attract its armature m^s , closing the circuit between the link and the trunk line as will shortly be described. The plate b^{1w} may be common to all the group of trunk lines running between the switch and one other receiving switch, or separated, and each segment connected to a branch b^{14} , of wire bv . The contact plates b^{1w} of the subscribers' sets are insulated and independently connected to the selector plates. From each subscriber's or trunk line wires, run branches lettered a^2 and b^2 , to contact pieces in the set of this subscriber on the frame of each transmitting switch board of the group, through which the said line is adapted to be placed in connection. These contacts form part of each of the sets of contacts around the frame of each switch board. 125 130

The lines each have contact pieces a^2 , b^2 upon the different switch boards of the transmitting terminal switches and thus the branches a^2 and b^2 are adapted to be placed in connection with the link wires of any link. The current from battery D' is sent through the selector AB to the appropriate branch wire b^2 and thus operating the magnet M^8 of the terminal switch to which said wire runs.

10 When the circuit closing arm is operated, the contacts b' of the operating circuit are broken, and the contacts b^3 closed, thereby transferring the circuit from operating circuit u to the retaining circuit v and magnet M^v , breaking the continuity of circuit u at u^2 , thus preventing any other transmitting circuit closer from making connection with this line. There is a separate magnet M^v and separate operating and retaining circuits and contacts therefor for each communicating line. The operation of the terminal circuit closer T_3 is necessary to the final completion of a through talking circuit from a calling subscriber to a called subscriber, and such a circuit contains but two breaks at central, both closed by magnets M^8 . The contacts obtained at each break in the talking circuit are thus retained closed by magnetic attraction, and in practice this is found superior to spring jack contacts. When this switch operates, the magnet M^{16} closes the circuit for the controller magnet M^1 as follows,—battery D^1 , pole n^2 wire c^6 , contacts m^{16} closed by magnet M^{16} , wire c^7 , brushes e^2 , plate i^2 circuit breaker cb , wire g^3 magnet M^1 , d^4 , wire c^5 , and battery D^1 , intermittently advancing the controller as a time limit for conversation. The magneto call circuit is then completed as follows:

40 generator CG, contact spring e^8 , plates i^3 and i^7 , wire c^6 , and thus to the b side of the metallic circuit, thus established, over said circuit, in one or both directions, according to completion, to the a -side of the circuit to wires j and O' contact springs e^7 , plate i^7 of the controller, thence to the other pole of the generator CG. This generator may develop either a direct or an alternating current as desired, as long as it will operate the bell of a subscriber's outfit. By extending the plates i^3 and i^7 of the controller, and using retardation coils to render the current inaudible, and prevent interference between two or more conversation circuits, this current may act as a basis for the speaking current. In such a case the subscriber's bells would continue to ring until the subscriber cuts them out of the circuit at his station. When an alternating current is developed

50 by this generator CG, I prefer to tone it. When the link is being operated with subscriber No. 92, with whom we are dealing, the circuit is closed through both sides of the link circuit, as described, over the line wires a and b leading to the station apparatus shown in Figure 1. When this occurs the circuit is completed and the current from the magneto generator will pass over both limbs of the metallic circuit ringing the bells on subscriber No. 92's line informing him that the circuit to the trunk line is complete, and ready for the next operation of the commutator. This is on the supposition that subscriber No. 92 is obtaining connection with a trunk line T_a , T_b . If instead of selecting a trunk line he had selected a subscriber's line No. 42 in broken lines in Figure 5, the bells of that subscriber would have been rung also informing him that he was wanted at the telephone, at the same time, that subscriber No. 92 received his return signal. The absence of a return signal to the operating subscriber informs him that the desired person is busy, or that the accommodations of switching devices provided by the company are insufficient. And if he hears the commutator of his outfit operate, he knows that he has obtained possession of switching apparatus. So that the operation of the commutator accompanied by no bell signal will indicate that the desired line is busy. And absence of the commutator's operation indicates an inability of the line to get control of central switching apparatus. And when the commutator is set for operation it will remain there till it gets connection to central, the call remaining stored. The link switching apparatus will make a responding connection at any time before it is restored. So that if a desired subscriber is busy, the calling person, may, by waiting, get connection with him the minute he gets through.

55 When a subscriber's circuit and the link switching apparatus connected thereto are restored, the magneto signaling current is again sent out by means of detent d^5 which closes the contacts d^7 and d^8 of the magneto CG' to link wires L_a and L_b over the line momentarily notifying the subscriber of this fact; if he is immediately called again the calling signal is distinguished by its length. If, now, the called subscriber does not answer this signal, subscriber No. 92 may, as shown in Figure 1, turn the crank of his magneto mg sending a current over his circuit again ringing the bells of the called subscriber. In this way the calling subscriber may send additional signals to the telephone bells of the called subscriber if the latter does not answer the first signal which, as described, is automatic. I have shown the magneto mg as a possible arrangement. It may, however, be entirely omitted from the subscriber's outfit and the contacts ax and ay be omitted from the line a so that the line a may be permanently connected to the switch lever S^1 . On the other hand the automatic ringing of bells may be omitted and the magneto used entirely. The trunk

line is unaffected by the ringing current, until another subscriber is in the circuit.

I have referred to a restoring device whereby the subscriber may at any time after he has sent in his first impulse, restore all his instruments to their normal condition. Also how these instruments may be restored at the end of any predetermined time and all connections with other circuits be cut off. It is now my purpose to describe these devices. There are a number of different arrangements which I have contemplated. I might provide a third wire running from the subscriber's station to the central station, to which he is connected, and pass it through magnet M' to battery, thence to ground. By grounding this third wire at subscriber's station I might operate this magnet operating the switch Q to its normal position and thus, as described, close the restoring circuit at this point. This wire would be closed through the automatic links to a similar wire of other subscribers' circuits or trunk line circuits in the same manner as the two line wires a and b are connected to their circuits. The third wire however, I believe to be unnecessary and undesirable.

When the b side of the metallic circuit including the link wires, is grounded by a commutator for the first time, we have seen how it closes the local circuit for magnets Ml^2 and Ml by means of relays M and M^2 in parallel between dynamo D and wire Lb , operating the controller and the B-portion of the selector. A third parallel circuit is also established as follows; dynamo D , wire c' , wire, magnet M^7 , wire, to springs eo , plates io , and i , brush e wire c , to link wire Lb , thus attracting the restoring switch Q to its open position. After the completion of the first advance of the circuit controller the circuits are altered. The magnet M is cut out by its parallel circuit being broken at brush e^{11} and plate i^{11} ; and the plate i^4 , connected to plate i , brush e , and link wire Lb , is connected to brush e^4 , after the controller has completed the signal on the subscriber's bells, and thence by way of wire q^4 to the primary coil of magnet M' , wires q^2 , c' to battery D , so that as often as the side b of the metallic circuit is grounded a part of the current from battery D will pass through it and attempt to attract switch Q to its closed position which is normal. A secondary coil m^{91} around magnet M' includes another relay M^9 , and if the current in the primary coil of magnet M' is intermittent, induced currents from the secondary coil energize magnet M^9 , closing the contacts m^9 , causing magnet M^7 to be energized retaining switch Q in its open position. If the impulse lasts too long, as will happen when a subscriber closes his restoring switch Rs^2 or S^1 , contacting with

lever L , the induced impulse in magnet M^9 will die, the circuit closer m^9 will be broken, the magnet M^9 alone energized, and the switch Q restored; it is essential, that one of the contacts m^9 be a spring in order that the impulse be long enough to operate ratchet magnets thus preventing magnet M^7 from being deenergized. When one contact is a spring the contact lags, after the induced current is dead, and if the momentum of the armature is increased, the length of contact is also increased. By proper adjustment of yielding elastic contacts, and strength of magnet coils and momentum of the armature, this compound relay becomes adapted admirably for the work to which it is applied. Upon the adjustment depends the length of impulse which may be used for the ratchet magnets, or relays therefor. After the strength and momentum of the relay have been fixed, additional adjustment for impulses of varying length is secured by adjusting the distance between the spring and armature contacts. A make and break of circuit b to ground closes these contacts, so that the line wire b may be grounded as often as desired for operating additional ratchet mechanism, and this delay will remain undisturbed in position. But the minute a restoring circuit closer is operated, it operates the switch closing the restoring circuit at this point.

In the normal position of the controller Cc , the restoring circuit is broken by brushes e^9 and plate i^9 , but after the first step in advance, the controller closes the circuit at this point the circuit being simultaneously broken by the switch Q , so the detents are free to perform their function during operation, but are withdrawn when switch Q closes the following circuit; battery D' , wire c^5 springs e^9 , plate i^9 , wire n^3 , switch Q , contact q , wire n , magnets M^6 , M^5 , M^4 , wire c^6 , to battery D' . The subscriber may ground his line by closing the contacts Rs^2 ; or he may do this by hanging up his receiver and operating the circuit closer L , as described. When the circuit controller is resuming its normal position the circuit through the selector and controlling the magnet M^8 of the transmitting switch Ts is broken, and that switch resumes its normal rotation. The branch t^{10} of the retaining circuit t^8 , from t^8 of the switches Rs , is normally closed at contacts t^{12} , controlled by the detent d^4 , while the branch t^{11} of this circuit is normally open through the springs e^8 and plate i^8 of the circuit controller. When the detent is withdrawn, the circuit t^8 is broken at t^{12} but remains closed through i^8 until the circuit controller is nearly restored to normal. This is to prevent the receiving circuit closer Rs from closing circuit to another person's line and operating before the link apparatus is ready

to receive new impulses. The plate i^8 is so adjusted that the circuit closer Rs is released before the relay circuits are completed to the link wires so that if the line wire b is kept 5 grounded by the person restoring it has no effect on the link which is severed therefrom. The restoring circuit is not broken at i^9 until the circuit i^8 has been broken at i^{12} and i^8 long enough to release the circuit 10 closer Rs . The specific form of ratchets, detents, brushes, and other mechanical structures I have not deemed it necessary to show, as they are familiar to those skilled in the art. It is necessary to note also, as 15 once before stated, that the pawls operated by the magnets M_1 and $M_1^{1/2}$ and $M_1^{1/3}$ are normally out of engagement with their respective ratchets. The stop c^3 prevents the controller Cc from going further than its 20 normal position. The contact plate i^{10} is supposed to be in such position on the circuit controller, that when it has completed or nearly completed its rotation, this plate will be brought under the contact springs 25 e^{10} . When this happens the following circuit is established: dynamo D , wire q^4 , containing the primary coil of magnet M' , spring e^4 , plate i^4 , plate i^{10} , in permanent electrical connection with plate i^4 , contact 30 spring e^{10} , to wire t' , thence to ground at E . Current flows from the dynamo through the magnet M' and temporarily through magnet M' owing to the closing of contacts m^9 under the influence of an induced current in magnet M^9 whose origin is in the secondary coil 35 of magnet M' . When this induced current is dead, the contacts m^9 open again automatically, the armature dropping therefrom and the magnet M' alone is active, restoring 40 the lever Q to its normal position, withdrawing the various detents from the various ratchets and permitting the various instruments to return to their normal position shown in the drawings. When the instruments 45 are restored to normal position the current on branch bv , operating a magnet of the transmitting terminal switch T_s , is cut off by the springs e^6 and plate i^3 of the circuit controller. When this switch is released 50 its heavy heel re-engages with the collar w^9 and it continues to rotate with the arbor. The circuit controller returns to its normal position more slowly than the other parts maintaining the restoring circuit complete at i^8 until the selector and circuits have resumed their normal position. This 55 retardation is secured by the use of a fan or by an escapement or dash-pot or any other suitable means, like that shown in Figure 10.

At the same time that the magnet M^9 is operated the side of the metallic link Lb is closed direct to ground through the circuit as follows: The line wire Lb is grounded 60 through wire c , plates i , and i^{10} , the con-

tact spring e^{10} , wire t' to earth at E . Thus the restoring circuit and devices of all lines, trunk or other link lines continuous with b , are operated and all devices and circuits maintaining a conversation circuit are restored to normal position. This does away with the necessity of a time circuit controller at a higher central station, and they may consequently be reduced in size, and their operating circuit contact plate i^2 cut 70 off at a point to prevent the controller from rotating to a useless distance. In such a case the plates i^9 , i^8 , i^4 and i^6 would be longer than i^2 and plate i^{10} would be omitted. Conversely, if all circuits be obtained through a 75 higher central, as hereinafter referred to, the links at that central alone may be provided with the limit controller.

Over the circuit established by a link between two communicating lines any sort of 80 a current may be passed without disturbing the electrical continuity of the lines so that by any proper means a central battery may be utilized to furnish the current for talking purposes, as is well known in the art. 85

In Figure 4 and in full lines in Figure 5 I have shown a trunk line T . Each trunk line is preferably connected to a set of terminal contact points on each of the switch boards T_s and Rs , and the only difference 90 in their organization is that I supply current to all the trunk line contacts b^{tw} of the trunk line sets connected to a switch board from one line b^{tv} , or branches b^{17} . But in other respects these trunk line connections 95 correspond closely to a subscriber's line connections.

So organized a trunk line may be used in either direction. This organization will not be liable, on unusual coincidences to a 105 collision on a trunk line, between two subscribers, on account of a non-interference circuit. If it is desired to avoid this arrangement, trunk lines should be separated, those for transmitting impulses to other 110 groups connected to the transmitting switch boards T_s , those for receiving impulses from other groups, connected to the receiving switches only and relays altered to suit. In other words, all connections at transmitting switch boards at one end, and all connections at receiving switch boards at the other end of each trunk line may be cut off. This organization slightly reduces the 115 amount of work a given number of trunks can accommodate.

I will now describe how subscriber No. 1 may put himself into connection with any one of the trunk lines shown in Figure 4. In Figure 1 on the keyboard S , the upper 120 cross bar and the left hand cross bar s' are grounded permanently, so that as the commutator S' operates, as before described without using the plug, the line wires a and b each are grounded once. In Figure 3 when 125

the line wire b is grounded once the circuit controller Cc is advanced one notch and from that point its local circuit containing magnet M^1 is closed and the circuit controller continues to advance as heretofore described. At the same time the magnet M^2 is grounded once by a parallel circuit. When the line wire a is grounded the magnet M^3 is operated once, advancing the contact arm b^{10} to the first contact plate b^{11} of the instrument A having a wire bt^v connected thereto. Shortly a current is thrown on to the wire b^{16} , connected to contact arm b^7 by the circuit controller Cc through springs e^6 , and contact plate i^6 from dynamo or storage battery D' . In continuing this circuit, the current flows from contact arm b^7 , contact plate b^8 , wire b^9 , contact plate b^{11} , its branch wire bt^v , thence as shown in Figure 4, to the contact plates b^{1w} on the frame of the link terminal circuit closer Ts operating it. By this means the subscriber may obtain the use of a trunk line to any central station with which his central station may be connected. In order that when a trunk line has been connected to a terminal switch at one end, it cannot be connected by another person at the other end, I provide, for each trunk line another or third wire and an individual battery D^2 , see Figs. 4 and 5, and relays and circuit apparatus, which, when a transmitting circuit closer has established connection at one end, as at a sub-central, no transmitting circuit closer at the other end, as at main central can connect itself thereto; and yet any receiving circuit closer may be controlled therefrom. Not only this but it is impossible for transmitting switches to maintain connection with one trunk line at both ends. When one end has been connected to a transmitting circuit closer, as in Fig. 4, the retaining circuit of that switch, conductor v , operates magnet Mv' contained therein, closing the contacts u^5 , closing the following circuit; battery D^2 , wire X contacts u^5 to trunk wire Tb , through magnet X^2 , Fig. 5, contacts u^8 , normally closed, wire X , battery D^2 . This circuit energizes magnet X^2 opening the contacts u'' and U^{12} of the operating and retaining circuits of the transmitting circuit closers Ts at this station, U and v , but in no way affecting the receiving circuit closers Rs . So that the latter may be connected to the trunk line by the operation of relay Mt^2 as in case of subscriber No. 92 in Figs. 1 and 2.

This non-interference trunk circuit when closed at the station at one end, shown in Fig. 4, is in derived circuit with one side of the metallic circuit Tb . If one of the transmitting circuit closers Ts in Fig. 5 operates first, it closes a derived circuit over the other side of the metallic circuit, Ta , as follows; battery D^2 , Fig. 5, wire X , contacts u^7 closed by magnet Mv^2 energized by the retaining

circuit of the operated switch Ts thence to wire Ta , to Fig. 4 wire X' , contacts u^6 , normally closed, wire X , to battery D^2 again, Fig. 5. This circuit operates magnet X' , opening the normally closed contacts u^9 and u^{10} , of the operating and retaining circuits of the transmitting circuit closers at this end of the line.

This third wire X may of course be omitted, likewise magnets X' , Mv' , X^2 and Mv^2 , and all the contact makers and breakers pertaining thereto, leaving the trunk line connected as in Fig. 2, in which case a subscriber No. 42, Fig. 5 might be substituted for the terminals in Fig. 5. This connection which has been described is preferably to the main central station so that before a subscriber proceeds to make connections upon his keyboard corresponding to the number of the subscriber whom he desires to call, he places himself in communication with the main central by merely operating his push rod.

As the non-interference circuit is in derived circuit with but one side of the talking and signalling circuit, when in use, and severed from the other side of the circuit, it has no effect upon the use of it.

The main use of this non-interference circuit is where but few trunk lines are required between distant points, to save wiring. For one circuit with three wires that can be used either way is better than two trunks having four wires.

The way in which he obtains connection with any other subscriber in the system is by duplicating the apparatus shown at the sub-central, namely, the automatic links, and by repeating his operating with his commutator, operating the selector and circuit controllers in the various links with which he may get connection and through which he may desire to secure connection with another subscriber.

In an exchange of 10,000 subscribers, each trunk line to the main central can obtain connection with a trunk line to any other sub-central connected thereto. To enable this to be done some trunk lines may be connected to receiving switch boards at main central, and transmitting terminal switches at the sub-central, and others have these connections reversed, or all trunk lines may be connected to both switch boards as herein shown. And the circuit controllers and selectors of one link at central can secure control of other trunk lines at this point as more fully described later on. It will be noted that the subscriber having once gained connection through a link and a signal returned to said subscriber indicating to him that the desired connection from his first operation is completed, the link devices, except the restoring portions thereof, are cut out of circuit in such a way that they can be operated no more until they have been

restored to their normal position. If now, the subscriber finds that he has made a mistake in his connection, he may, by pressing R_s' upon its contact, being directly connected to the side b of his metallic circuit, ground said side, restoring all the devices of all the link circuits with which he may be in connection at that time, to their normal position.

- 10 If, however, subscriber No. 1 desires connection with any other subscriber in his group, he needs only to make connection with the junction numbered to correspond with that subscriber, obtaining connection 75 with him directly, or he may gain such connection by a round trip to central and back, thus obtaining uniformity in his operations. This may be desirable to the more inexperienced operator. Any subscriber in this exchange 80 may obtain direct connection with central without being required to perform the various operations which would be required if he were compelled to obtain a connection therewith by way of an intermediate 85 central station. When lower left hand subscriber 1 wishes to obtain connection with lower left hand subscriber 3, Figure 9, he places the plug P upon the junction of the cross bars s and s' , shown in Figure 1, which 90 are labeled to represent that subscriber and by operating his commutator, can obtain direct connection with him. This operation will only answer when he is obtaining connection with a subscriber connected to 95 the sub-central station to which he is connected. When, now, the lower left hand subscriber 1 wishes to obtain connection with another subscriber 1 connected to his intermediate central station, and in describing 100 this operation I describe all the operations necessary to an exchange of 10,000 subscribers wherein all the subscribers are grouped in hundreds, he may make connection with the cross rods labeled to represent 105 the trunk lines connected to this intermediate central. These cross rods I have designated in Figure 1 as permanently grounded, so that by operating his push rod the subscriber will obtain a circuit through 110 any one of the idle trunk lines with which his sub-central station may be connected to the intermediate central station. From this point if he wishes subscriber No. 4-2 he grounds the junction labeled 4 and operates 115 his commutator push rod; and upon the reception of his return signal indicating the desired connection, he places the plug P upon the junction labeled to represent subscriber 2 and again operates his commutator. 120 60 When he receives the return signal he is informed that the desired connection is completed for talking. The signal which he received is also received by the called subscriber informing him that he is wanted at 125 the telephone. This talking circuit will last 130

until the time limit, set by the circuit controller C_c , has expired, or until either subscriber grounds the b -side of the talking circuit, on either of which occasions all of the instruments and circuits in series will 70 be restored to their normal position.

If, now, the exchange is arranged to accommodate a million subscribers, as shown in Figure 9, an additional junction, labeled perhaps $L.D.$ for long distance, is provided 75 and an additional connection through the link selector AB is provided to correspond with that junction and the commutator so modified as to complete a different combination of circuit connections to suit, or I may 80 run one of the circuit connections b_2 , which may run in a system of 10,000 subscribers to the terminal contacts of a subscriber in the group, to the proper sets of contact points upon the switch board representing 85 an additional set of trunk lines reaching through to the main central station for the million subscribers. To obtain connection with any one of a million subscribers would require four operations on the part of any 90 subscriber, provided such connections are required to be made through the main central office shown in Figure 9. These operations would be as follows: Complete the junction LD not shown, but thus described for a million 95 subscribers to earth by plug P , operate the commutator thus securing control of one of the trunk lines to the main central station for the whole exchange; then by operating the commutator three successive 100 times, each time making junction with the proper character upon the key board, as, for example, 2, 3 and 4 for subscriber 2- 105 3-4, or 99, 57, 83, for subscriber 99-57-83, and waiting after each operation for the return signal. Subscriber No. 999,999, would be called by numbers 99-99-99, in succession.

It is not necessary that in each group there should be fully one hundred subscribers 110 when the exchange is based on a system of hundreds. Likewise, it is not necessary that one hundred subcentral stations should be connected to a single intermediate central station, nor would it be necessary that one hundred intermediate central stations be connected to a main central station, as the exchange may be organized in the beginning 115 to accommodate the desired number of subscribers and the groups of converging lines to any central station of any order be incomplete, having perhaps but a few sets of trunk lines or but a few subscribers to a central station. The designating numbers of the omitted circuits will of course be omitted 120 from the telephone directory, and the number of trunk lines reduced accordingly. It lies within my invention to put in trunk lines from any central station to any other central station that the demands of 125 130

business or the demands of private individuals may require and it would only be necessary to designate such connections or interconnections at the subscriber's key board by the proper characters. In Figure 9 the designation of the lower left hand subscriber 1 in the telephone directory of the exchange, preferably would be 1-1-1. The designation of lower right hand subscriber 2 would be 2-4-2. If twenty-five talking circuits should be arranged to converge to the various central stations the letters of the alphabet might be used, or numbers 0 to 24, or any other characters which might be fitting. If fifty talking circuits converge to any central station, fifty different designating characters would have to be employed in various combinations to represent the various relations of the subscribers to the system. When one hundred subscribers are arranged in a group as is preferred the numbers 0 to 99, inclusive, would be used in preference to designate the various talking circuits adapted to be selected. In the telephone directory the designations of subscribers in an exchange for 10,000 might be 48. 22; 51. 27; 1. 99; etc, etc. The periods in these numbers might be omitted but the use of them prevents confusion which might otherwise arise. Without the periods or separating marks, the last subscriber mentioned might be designated 0199, and any subscriber endeavoring to obtain connection with him would operate junction 01 and then junction 99 first gaining connection with the central station to which both subscribers are connected.

This system of grouping permits a great reduction in the cost in the installation and maintenance of exchanges. In most present telephone exchanges, for example, each subscriber has an individual circuit running direct to central. My invention contemplates the use of trunk lines from a local point to which subscribers are connected, to the central station. Thus one thousand subscribers now requiring one thousand circuits connected to central, may be accommodated by 120 trunk lines for the greater part of the distance. This is based on the experience of present systems in which one hundred subscribers require twelve talking circuits at any one time, resulting in the provision of twelve double plug links, on the multiple switch board. I prefer the number of automatic links which may be found necessary for business. The celerity with which a connection is made through a link in practice, renders a reduction of the number of links possible, except at a main central station, where the number must equal a trifle over one half the number of different trunk lines.

Figure 9 shows how the main centrals of a million exchange may be divided up

among the subscribers, enough centrals being provided to do the business of all the trunk lines. To the central for a ten thousand exchange, one hundred sets of trunk lines converge. And if each set contains six talking circuits, from one subcentral, each talking circuit can obtain connection with any one of 99 other circuits, of which in one of my arrangements one runs to each subcentral, so that the sets of trunk lines are divided into six divisions, each division containing a trunk line to every subcentral and from any subcentral.

The four central exchanges shown on Fig. 9 merely illustrate that a plurality (any number in fact with sufficient trunk lines) of such centrals may be used to provide the necessary accommodations in the exchange for a large number of subscribers.

When I apply my invention to long distance telephony, I may omit the circuits and devices by which any subscriber may at any time restore the apparatus on his connected circuit, and leave only the time restoring circuits and devices. So that different sources of current D, may be used at different central stations on the line, being cut off from the link after connection is established through said link, thus preventing the confusion and liability to restore if three or more sources were connected through restoring circuits to the line at different stations, caused by one battery being grounded through another. If currents of equal value are used, a separate battery D may be used for each central station. It is obvious that one calling generator, might be used for all the links at a central station, and that all current supplying devices may, for a large exchange, be located at one point under the care of one attendant.

Any one of a vast number of trunk lines may obtain connection with any other of all the trunk lines in this system by enlarging the capacity of terminal switch boards as described.

In Figure 9 I have shown in diagram the connections between the subscribers contemplated in my system, and the various exchange centers. This figure shows how the connections for one million subscribers may be made. The squares at the top and bottom of the figure, numbered 1 to 4 represent the subscribers. There may be any number of them connected to one subcentral, of which sixteen are represented, being the single circles numbered 1 to 4. The same or a less number may be connected with intermediate centrals, represented by the small double circles 1 to 4. Likewise the intermediate centrals may be connected with main centrals, of which there may be but one, and the instruments so organized that any one of the lines from the lower exchange centrals may automatically be put in connec-

tion with any other line from the lower exchange centrals. Terminal switches of a capacity equal to the whole number of trunk lines would be required in such an organization, and each branch from the selector would have forked lines, like b^{17} Figure 3, all the forks of a branch running to the sets of contacts of the trunk lines which connect with a particular exchange as is the case 5 from subcentral to a main central. Or I may 10 preferably, for the purposes of this invention, provide as many different exchange centrals at one, or different points, as there are sets of trunk lines, and have one trunk 15 line of each set connected to each central. This organization would in an exchange of a hundred groups, permit a trunk line from a lower central to gain connection with one trunk line running to any other lower central, but all of the former trunk lines would 20 be unable to get connection individually with all of the latter.

In the figure I have shown how the subscribers are connected to the subcentral by 25 lines y^1 , of which there is one for each subscriber. These subcentral are connected to the main central by trunk lines either z or z^1 . Each trunk line set z may be composed of several circuits, each of which is 30 enabled to gain connection with any other trunk line connected to the main central, one from each subcentral, the terminal switches having a capacity equal to the number of trunk lines times the number of lower 35 centrals to be obtained therethrough.

z^1 represent trunk lines connected each to a main central where it is enabled to gain connection with one trunk line to each of a hundred different centrals of lower order. 40 And as many different mains located at one or different points must be provided in such an organization as there are different trunk lines in each set, required to do the business, the terminal switch boards at said 45 mains having a capacity of about one hundred lines. These organizations may be used each alone, for the whole system, or both combined.

x represents the trunk lines through which 50 a subscriber is enabled to gain connection with any one of the intermediate centrals from the main central. From each main runs a line to each intermediate central. When the terminal switches have a capacity 55 of but one hundred trunk lines, in the system described, the line x is composed of but one circuit. But when the terminal switch boards have a larger capacity as described for the same system, these lines x may represent a number of trunk lines, the desired set being selected at the will of the subscriber, the particular trunk line of the set that is connected to depending on its freedom, and its order.

60 y represents the connections from an inter-

mediate central to a subcentral. This represents several trunk lines, or one, according to the capacity of the terminal switch boards used similar to the lines z and x .

In an exchange of hundred groups for ten thousand subscribers, the only exchanges necessary are the subcentral, and one intermediate central. Such a system allows for one hundred groups, each group containing one hundred subscribers. In such an exchange, the subscribers in each group are designated by a different character, and each subcentral is designated also by a different character. So that subscriber No. 42 of group G would have as designating character G-42. And a calling subscriber would operate impulses corresponding to central G and subscriber No. 42. Preferably, however, and this is a salient feature of my invention, I apply the same characters in repetition to the subcentral, that I apply to the subscribers, as this permits a key board at the subscriber's station to be much simplified, so that instead of having a different key for each operation in getting from central to subscriber the same set of keys may be used for all the operations successive from central down. For example, if subscriber 2-43 is being called, the calling 70 person after gaining connection with central, operates key 2 getting control of a trunk line to subcentral No. 2, and then operates key 43 to obtain the subscriber 43, of the group. Although it is not necessary I preferably omit a separate key for getting connection with the central exchange, for 75 80 85 90 95 100 105 110 115 120 125 130 135 140 145 150 155 160 165 170 175 180 This requires three operations of the key board after gaining connection with central.

I do not limit the scope of this invention to the use of the particular switching and selecting apparatus shown, as it is evident that a great many different forms might be substituted therefor. Any selector that will select between a number of lines will answer instead of the selector AB; and any switch 10 that will fasten upon one line to the exclusion of other lines will accomplish the results of the terminal circuit closers shown; and all sorts of signal transmitting instruments might be substituted for my commutator; and other obvious changes might be made.

And I do not intend to be understood as limiting my invention to use in a grouped exchange, for it is obvious that many parts 20 of it might be used without the grouping idea.

When this exchange system is used for other than telephone purposes, as telegraphy, or telautography, or for printing telegraphy, the instruments of such systems would take the place of the telephone outfit of the subscriber, shown in Figure 1, and a hand operated switch substituted for the switch lever S1.

30 By trunk lines I mean trunk circuits, some of which may be a combination of other trunk circuits, interference being prevented by the use of resistances, condensers and induction coils as is well known in the art.

By "communicating or line circuits" I mean either subscribers' or trunk circuits, either single or constructed on the principles above referred to.

40 And parts of my invention are obviously adapted for single wire grounded lines.

What I claim and desire to secure Letters Patent for is:

1. In a telephone exchange system, lines, 45 automatic switches for establishing connections between said lines, a restoring switch for causing the restoration of said automatic switches, an operating magnet for said restoring switch, a retaining magnet effective to prevent the operating magnet from actuating the restoring switch, and inductively controlled means for rendering said retaining magnet ineffective, permitting the operation of the restoring switch by said operating magnet.

2. In a telephone exchange system, lines, 50 automatic switches for establishing connections between said lines, a restoring switch for causing the restoration of said automatic switches, an operating magnet for said restoring switch, and a retaining magnet acting upon the restoring switch in opposition to the operating magnet for preventing the operation of said switch when 55 both magnets are energized.

3. In a telephone exchange system, lines, 60 automatic switches for establishing connections between said lines, a restoring switch for causing the restoration of said automatic switches, an operating magnet for said restoring switch, a retaining magnet effective to prevent the operating magnet from operating the restoring switch, a control relay, a winding on the operating magnet for inductively operating said relay, and a circuit 65 controlled by said relay for rendering the retaining magnet effective, said relay acting upon release to render the retaining magnet ineffective, permitting the operation of said switch.

4. In a telephone exchange system, lines, 70 automatic switches for establishing connections between said lines, means for sending impulses over an established connection, a restoring switch for causing the restoration of said automatic switches, an operating magnet for the restoring switch energized by impulses of current sent over the connection, a retaining magnet effective to prevent the operating magnet from actuating said switch, and a relay inductively operated from said operating magnet when said impulses are of one character to render said retaining magnet effective and releasing on impulses of another character to render the 75 retaining magnet ineffective.

5. In an exchange system, a line, a circuit controller, a receiving terminal circuit closer for extending said line to said controller, a release magnet for releasing said controller 80 to its normal position, a retaining circuit for maintaining the terminal circuit closer in operated condition, said retaining circuit closed at one point through contacts of said controller and at another point through contacts of said release magnet, and means for opening the retaining circuit at both points.

6. In an exchange system, a line, a circuit controller, an automatic receiving switch for extending said line to said circuit controller, an operating and retaining magnet for said switch, a retaining circuit including said operating and retaining magnet for maintaining the receiving switch in its operated condition, a release magnet for releasing said controller to its normal position, said retaining circuit closed at one point through contacts of said controller and at another point through contacts of said magnet, and means for opening the retaining circuit at both points.

7. In an exchange system, a line, an automatic transmitting switch, an automatic receiving switch for extending said line to the transmitting switch, a circuit controller for controlling the operation of said transmitting switch, a release magnet for releasing said controller, a retaining circuit for holding said receiving switch in its operated condition, said retaining circuit having two 125 130

parallel branches, one closed through contacts of said controller and the other through contacts of said release magnet, and means for operating said controller and release magnet to open said retaining circuit.

- 5 8. In an exchange system, a line, an automatic transmitting switch, an automatic receiving switch for extending said line to the transmitting switch, a circuit controller for 10 controlling the operation of said transmitting switch, a release magnet for releasing said controller, a retaining circuit for holding said receiving switch in its operated condition, said retaining circuit having two 15 parallel branches, one closed through contacts of said controller, and the other through contacts of said release magnet, and means controlled over said line for operating the release magnet to open the retaining circuit 20 at one point and for operating said circuit controller to open the retaining circuit at another point.

9. In an exchange system, a subscriber's line, an automatic receiving switch for 25 extending said line, an operating circuit for said switch, a preliminary retaining circuit for said switch closed upon the operation thereof, a circuit controller, a release magnet for said controller, a second retaining 30 circuit having two branches, one closed through contacts of said controller and the other through contacts of said release magnet, means controlled over the line for operating the release magnet to open one of said branches and for operating said controller to open the other of said branches prior to the 35 reclosure of said first branch.

10. In an exchange system, subscribers' lines, a plurality of receiving switches for 40 extending said lines, an operating circuit for said switches having parallel branches, one for each switch, circuit controllers, release magnets for said controllers, a retaining 45 circuit for said switches having parallel branches, each leading through the contacts of a circuit controller and the contacts of a release magnet, and means controlled over a calling line for operating the release magnet and circuit controller to open the corresponding retaining circuit.

- 50 11. In an automatic exchange system, a link circuit having two conductors, a selector having two operating magnets each connected to a conductor of said link for switching operations, a circuit controller connected to one of said conductors, a receiving circuit closer and a transmitting circuit closer for said link, telephone lines for connection to said link at either circuit closer, a commutator connected to each of said lines for op-

erating the selector magnets, a release magnet for said circuit controller, a retaining circuit for said receiving circuit closer closed through contacts of said circuit controller and contacts of said release magnet, and 65 means for operating said release magnet and circuit controller for opening said retaining circuit.

12. In an automatic exchange system, a two conductor link circuit, a selector having two operating magnets each connected to a conductor of said link for switching operations, a circuit controller connected to one conductor of said link, a receiving circuit closer and a transmitting circuit closer for 70 said link, telephone lines for connection to said link at either of said circuit closers, a commutator connected to each telephone line for operating the selector magnets and for starting said circuit controller, a release magnet for said circuit controller, a release magnet for said selector, a retaining magnet for 75 said receiving circuit closer having a circuit closed through contacts of the circuit controller and contacts of its release magnet, and means controlled over a telephone line for operating said release magnets to release 80 said selector and circuit controller.

13. In a telephone system, lines, a receiving switch and a transmitting switch each 90 comprising a single operating shaft and a plurality of rotating circuit closers, a plurality of links, each terminating in contacts of a receiving circuit closer and contacts of a transmitting circuit closer, selectors for 95 said links, means for operating a receiving circuit closer to extend a calling line to a link, means controlled by impulses over said calling line to position the selector and means controlled by said selector for operating the 100 transmitting circuit closer to extend the calling line to a called line.

14. In a telephone system, lines, a receiving switch and a transmitting switch, each comprising a single operating shaft and a 105 plurality of rotating circuit closers, a plurality of links, each terminating in contacts of a receiving circuit closer and contacts of a transmitting circuit closer, selectors and circuit controllers for said links, means for 110 operating a receiving circuit closer to extend a calling line to a link, means controlled by impulses over said calling line to position a selector, means controlled by said selector for operating the transmitting circuit closer 115 to extend the calling line to a called line, and a retaining circuit for said circuit closers controlled by the circuit controller.

In testimony whereof I affix my signature.
MYRON F. HILL.
